ROBERT LUCIEN D'ESPUJOLS, OF LA VARENNE, ST.-HILAIRE, FRANCE.

BOILER-SUPPLY SYSTEM.

Application filed April 4, 1923. Serial No. 629,945.

To all whom it may concern:

Be it known that I, ROBERT LUCIEN D'ESPUJOLS, citizen of France, residing at 8 Promenade des Anglais, La Varenne, St.-Hilaire, Seine, France, have invented certain new and useful Improvements in Boiler-Supply Systems, of which the following is a specification.

This invention relates to systems for controlling the supply of liquid to a boiler and is characterized by the arrangement and employment of devices so disposed and connected that they permit automatic feeding of the boiler without requiring supervision, the working being such that the liquid supplied to the boiler in a given unit of time always corresponds to the amount of liquid vaporized.

A feature of the invention consists in the fact that the fluid which operates the prime mover of the boiler feed pump is automatically controlled by a device comprising an expansible container so placed in communication with the boiler as to take up alternately or simultaneously the vapour or the liquid in accordance with the liquid level in the boiler. This container conveniently consists of a pipe horizontally disposed in the plane of the desired liquid level. This pipe or container by its expansion or contraction actuates an element to operate a valve which admits or cuts off the motive fluid of the prime mover of the feed pump.

If desired an adjusting device comprising a chamber with expansible walls in permanent communication with the boiler may be employed for the purpose of compensating for the varying expansion of the expansible container due to variations in boiler pressure.

A further feature of the invention consists in employing a reciprocating feed pump prime mover having a distributing valve and in controlling this valve by devices operated by fluid pressure. For this purpose vapour under pressure from the boiler may be employed.

The accompanying drawings show diagrammatically by way of example a mode of execution of the invention.

Figure 1 is a diagrammatic view of the system of the invention applied to a boiler of any construction.

Figure 2 is a view of the whole feeding or supply system.

Figure 3 shows a vertical section on a larger scale of the details of the feeding apparatus.

Figure 4 is a detail plan view of the arrangement for shutting off the admission valve to the feed pump prime mover.

Figure 5 is a side view partly in section on a still larger scale than in Fig. 3, of the preferred detail construction of a removable adjusting or compensating device.

In Fig. 1, the line *a*—*b* indicates the normal water level in the boiler A. The above-mentioned expansible container which with its mounting is indicated by B in the diagram of Fig. 1 must be arranged in the horizontal plane passing through said line *a*—*b*.

This expansible container and its mounting (Fig. 3) consist of an expansible pipe 1 which is arranged in a fixed pipe 2 and is secured in said pipe at one end by means of a nipple 3 and a nut 4. The other end 5 of the pipe 1 slides freely in the fixed pipe 2. The whole arrangement is rigidly associated with the head of the cylinder 19 of the feed pump prime mover.

The expansible pipe 1 is connected with the boiler in the following manner: First of all it is connected with the steam chamber through a pipe 6 which is joined at the nipple 7. In the second place it is connected through the nipple 3 by means of a pipe 8 and by means of an introduced cooling worm 9 which is intended to take part of the latent heat, to the lower part of the water chamber.

The free end 5 of the expansible pipe acts upon an element such as a falling lever 10 which swings between two trunnions 11 which are secured to the support 12 of the pipes 1 and 2. The free end of the falling lever 10 (which is provided with an adjusting device 13 to be hereinafter described in detail) actuates an equilibrium valve 14 which regulates the admission of the driving fluid (steam or compressed air) to the slide valve of the driving cylinder. The valve rod 15 carries a member 16 to which two return springs 17 are attached, the other ends of which are suspended on the projections 18. This device ensures the return of the valve to its seat, as soon as it has been released by the falling lever.

Underneath the valve 14, is arranged the working cylinder 19, the controlling slide valve of which is indicated at 20. The piston 21 moves in the cylinder 19 and the other

end of the piston rod 22 carries the piston of the feed pump (P, Fig. 2).

A part 23 is secured to the piston rod 22, which part moves with the rod between the 5 two valve boxes which are fixed to the frame of the pump and may communicate with the boiler through the pipe 24 which conducts the steam to the chamber 25. At the end of each stroke of the piston 21, one of the 10 valves 26 is removed from its seat by the part 23. The valves are brought back to their seats by the springs 27 as soon as their actuation by the part 23 ceases. If one of the valves 26 is removed from its seat free 15 passage is given to the steam, which enters the appropriate chamber 28 and passes therefrom through the pipes 29 to one side or the other of the piston 31 movable in the cylinder 30. The rod of the piston 30 is 20 connected with the slide valve 20 through the extensible coupling 32.

The cylinder 31 is provided with two bores or parts 33 which communicate with a casing 34. When the piston 31 is at 25 either end of its stroke one of the bores 33 is uncovered. The steam which one of the valves 26 allowed to enter the cylinder 31 then passes into the chamber 34 and escapes freely therefrom through the 30 pipe 35.

The manner in which the device operates is as follows: Assuming the boiler to be under pressure and the water level to have fallen down to line *c-d* (Fig. 1) then the 35 boiler steam passes through the pipe 6 into the expansible pipe 1 and causes the extension of the same. The head 5 of said pipe engages the falling lever 10 and the latter in its turn removes the valve 14 from its seat which then allows the passage of the steam 40 (or any other driving fluid such as compressed air) conducted to the channel 36 (Figs. 2 and 3). The piston 21 at once is set in motion and consequently works the 45 feed pump. However, the rod 22 of the piston 21, upon being displaced, carries with it the part 23 which raises the valve 26 at the opposite end of the stroke of the piston 21. Hence the steam passes from the chamber 50 25 into the chamber 28 and is conveyed from there through the pipe 29 to the corresponding side of the piston 30. The latter is moved to the opposite end of its stroke, when it inverts the position of 55 the slide valve 20. The direction of motion of the piston 21 is then instantly reversed. In this manner the automatic working of the feed pump is obtained and the feeding lasts up to the moment when the water 60 level corresponding to line *a-b* is again restored in the boiler. At that moment the steam contained in the expansion pipe 1 is replaced by water and the pipe shrinks more and more. Consequently the falling 65 lever ceases to actuate the rod of the valve

14 and the latter is brought back to its seat by the springs 17, when the pipe 1 has resumed its minimum length. During the contraction of the pipe 1, the pump works with decreasing speed and finally comes to a standstill. So soon as the water level in the boiler sinks again, steam again enters the expansion pipe in place of the water and the above described cycle of operations is repeated.

It should be observed that the device, as above described, (which represents to a certain extent the theoretical working) only operated the pump during the first run. In practice the expansion pipe 1, when the water level approaches the normal level *a-b*, takes up both water and steam and it follows therefrom that it retains a mean equilibrated position between its terminal positions corresponding to its maximum expansion and contraction. Said mean equilibrated position determines the throttling of the working fluid introduced through the valve 14. Consequently the pump operates continuously, but its supplying capacity corresponds to the amount of vaporization in the boiler.

According to whether the boiler gives off larger or smaller quantities of steam, the running of the pump is either accelerated 95 or retarded. When the boiler no longer gives off any steam, the pump stands still; it begins to run again, however as soon as the boiler gives off steam and the water level sinks. By means of this invention, a 100 perfectly automatic and particularly safe feeding is obtained. The above described contrivance is completed by an adjusting device 13 (Figs. 3 and 5) which is arranged on the falling lever and the utility of which 105 is apparent from the following observations: The value of the expansion coefficient of the pipe 1 is not constant. It depends upon the boiler pressure, since as the steam temperature is higher and the latent 110 heat naturally greater, the higher the pressure in the boiler itself. Consequently the value of the differences between the temperature of the water and the temperature of 115 the steam varies with the pressure. It follows therefrom that the extensions or contractions of the pipe do not always take place under the same conditions, so that 120 there is no fixed regulation standard.

The adjusting device provided on the 120 falling lever 10, of which a detailed illustration is given in Fig. 5, makes it possible to remove the disadvantage of the aforesaid variations. As shown by Fig. 5 the device is arranged in a chamber 37 which is located in the lower part of the falling lever or attached thereto. Said chamber is closed by a plug screw 38 which carries the casing 39 of the adjusting device 13 itself. An adjusting locking nut 40 makes it possible to 125

adjust the casing 39 in the desired position. At the back of the chamber 37 placed opposite the adjusting device a hollow membrane 41 is provided, one surface of which is undulated and flexible. The inner space 42 of the membrane casing is connected with the coupling nipple 43 which is permanently connected to the boiler by a flexible tube.

- 10 Against the undulated surface of the membrane 41, there is pressed by a counter spring 44, a disc 45 which is connected with a rod projecting from the casing 37 which rod forms the member 46 by which the device actuates the valve 14. In the hollows of the undulations of the membrane are rings 47 and the disc 45 presses on the same.

The manner in which the adjusting device operates is as follows:

- 20 If the spring 44 is adjusted at a certain tension (normal condition), the disc 45 remains in its supported position on its seat when it remains in contact with the membrane 41 through the intermission of the rings 47. The length e at which the rod 46 projects from the casing 37 has the value corresponding to the initial theoretically constant regulation pressure. In reality, however, as the inner space 42 of the membrane is in constant connection with the boiler, the membrane, under the abnormal increase in the boiler pressure, is expanded and compresses the spring through the disc 45. Consequently the length e diminishes 25 and the travel of the valve 14 (Fig. 3) diminishes in proportion. The result is a retardation of the action of the pump, the behaviour of which is thus automatically altered in order to correctly adjust the 30 normal alteration of the regulating device brought about by the excess of pressure, that is to say, the new rise in temperature arising therefrom.

The adjusting device may also be arranged either at end 5 of the expansion pipe 1 itself or at the end of the rod 15 of the

valve 14, instead of at the falling lever 10, as described.

What I claim is:

1. In a system for controlling the supply of liquid to a boiler feed pump a fluid operated prime mover therefor and a device for automatically controlling said fluid comprising an expansible container and a conduit connecting said container with the boiler above the normal liquid level therein and a second conduit comprising a heat radiating portion connecting said container with the boiler below the normal liquid level therein.

2. A system for controlling the supply of liquid to a boiler comprising a reciprocating feed pump prime mover distributing valve for said prime mover and fluid pressure operated devices for controlling said valve.

3. A system for controlling the supply of liquid to a boiler comprising a reciprocating feed pump prime mover distributing valve for said prime mover and fluid pressure operated devices for controlling said valve said distributing valve being a slide valve and said fluid pressure being derived from the boiler.

4. In a system for controlling the supply of liquid to a boiler a boiler feed pump and a fluid operated prime mover therefor and means for automatically controlling said fluid comprising an expansible container connected with said boiler by upper and lower conduits, a cooling worm included in said lower conduit, said container comprising a tube rigidly mounted at one end and guided for reciprocating movement at the other end a projecting device connected with the movable end of the tube a pivoted lever engaging said device and an equilibrium valve controlled by expansion or contraction of said tube through the intervention of the projecting device and pivoted lever.

In testimony whereof I have signed my name to this specification.

ROBERT LUCIEN D'ESPUJOLS.
